Patented Nov. 26, 1963

197,000

SINK FAUCET OR A SIMILAR ARTICLE

Harper Landell, Whitemarsh, and Charles F. Molzen,
Philadelphia, Pa., assignors to Speakman Company,
Wilmington, Del.

Filed Sept. 7, 1962, Ser. No. 71,595

Term of patent 14 years

(Cl. D91—3)

FIG. 1.

FIG. 2.

FIG. 3.

FIG. 4.

FIG. 5.

FIG. 6.

FIGURE 1 is a perspective view of a sink faucet or similar article embodying our new design.
FIGURE 2 is a top plan view of the same.
FIGURE 3 is a front view of the same.
FIGURE 4 is a side view of the same.
FIGURE 5 is a back view of the same.
FIGURE 6 is an enlarged fragmentary sectional view substantially on line 6—6 of FIGURE 4.

We claim:

The ornamental design for a sink faucet or a similar article, as shown.
